To all whom it may concern:

Be it known that I, Leo Price, a citizen of the United States, residing in the city of Cleveland, county of Cuyahoga, and State of Ohio, have invented a new, original, and ornamental Design for a Gauge Mounting Used for Gauging the Dimensions and Contour of Articles Having a Compound Curve, of which the following is a specification, reference being had to the accompanying drawings, forming a part hereof:

Figure 1 is a plan view of a gauge mounting used for gauging the dimensions and contour of articles having a compound curve, showing my new design;

Figure 2 is a rear view;

Figure 3 is a front view;

Figure 4 is a bottom view; and

Figure 5 is an end view.

I claim:

The ornamental design for a gauge mounting used for gauging the dimensions and contour of articles having a compound curve, substantially as shown.
